David T. Siegel, Chicago, Ill.

Application August 31, 1936, Serial No. 98,626

6 Claims. (Cl. 200—6)

My invention relates to circuit breakers or switches and particularly to a switch of the multiple type in which a sweep arm is adapted to successively contact a plurality of switch points.

Difficulty has been experienced in the maintenance of switches of the sliding contact type through long periods of use, due to the wear incident to the abrasive action of pitted or oxidized faces of the respective contacts, with a consequent reduction in efficiency of electrical contact; and my invention relates to an improved arrangement whereby the abrasion heretofore found to take place is substantially entirely eliminated.

The desired result is secured by providing for positive mechanical separation of the contacts in a direction perpendicular to the faces of the contacts prior to any substantial relative lateral movement of the contacts. The result is secured by the use of mechanism so arranged that the contact arm or sweep arm is rocked as a preliminary to the lateral movement of the arm between adjacent contacts. This result may be brought about in a number of different ways, three of which are illustrated herein.

The theory on which the described improvement has been found to be correct, notwithstanding the fact that the break is comparatively slow, is that a slow break is not only unobjectionable when dealing with alternating current, but actually advantageous so far as the matter of arcing is concerned. This is due to the fact that by a slow break, one or more alternations are certain to take place during the break, as the result of which any arc that has previously begun will be extinguished.

I have found also that the useful life of a switch of this character is substantially increased by the use of double contacts, with mechanism for causing them to make a break in sequence whereby one contact, which may be termed the pilot, makes contact first when a circuit is to be closed and breaks last when a circuit is to be broken. Thus, all the possible arcing takes place in the pilot contacts, leaving the other pair continuously clean, unpitted and without abrasive wear. Such an arrangement of the contacts is particularly useful and valuable in connection with a circuit breaker in which the switch arm is bodily moved away from contact position coincidentally with the lateral shift of the arm.

The invention will be more readily understood by reference to the accompanying drawings, in which:

Fig. 1 is a side elevation of a multiple switch

constructed in accordance with my invention, the casing being shown in section;

Fig. 2 is a sectional view on the line 2—2 of Fig. 1;

Fig. 3 is a sectional view on the line 3—3 of 5 Fig. 1;

Fig. 4 is a sectional view through the center of the switch construction;

Fig. 5 is a bottom plan view of the switch casing;

Fig. 6 is a sectional view through a modified form of the switch construction;

Fig. 7 is a sectional view on the line 7—7 of Fig. 6;

Fig. 8 is a bottom plan view;

Fig. 9 is a fragmentary sectional view on the line 9—9 of Fig. 6;

Fig. 10 is a sectional view through a further modification, the construction shown in this and the succeeding figures being considered, in some respects, to be preferable;

Fig. 11 is a fragmentary view of the contact piece in an initial position; and,

Figs. 12, 13, and 14 are sectional views on the lines 12—12; 13—13; 14—14 of Fig. 10.

In the drawings and referring particularly to Figs. 1 to 5, I have illustrated a cup-shaped casing 10, preferably composed of ceramic material, and a cover 11. Mounted axially within the casing is a shaft 12, adapted to be turned by a knob 13.

Surrounding the shaft within the casing is a sleeve 14 composed of insulating material and provided with a head having a pair of ears 15. Transverse notches 16 within the head provide a seat for a pin 17 that extends through the shaft 12 and constitutes the means for driving the sleeve.

A driving arm 18 is seated over the sleeve by means of an aperture in the arm, the arm having lugs 19 struck out therefrom, one pair being provided at each side of the sleeve, the lugs engaging the ears 15 on the sleeve. These constitute the means for driving the arm 18. Carried at the upper or free end of the arm 18 is a stiff coiled spring 20, mounted on a pin 21. The free ends 22—23 of the spring respectively lying on opposite sides of a finger 24 formed as an extension from an upward projection 25, from a driving sleeve 26 that will later be described. A pin 27 fixed to the arm 18 separates the two ends 22—23 of the spring.

As best shown in Fig. 2 the driving arm 18 has shoulders 28—29 at diametrically opposite sides of the center opening in the arm and these shoulders respectively overlie the arms 30—31 of a

50

55

bell crank that constitutes the sweep arm or switch arm of the switch. The body portion 32 of the bell crank is curved to overlie the driving sleeve 26 and pivot screws 33-34 seated in the driving sleeve constitute the pivot for the bell crank. The other arm 35 of the bell crank constitutes the switch arm and carries a contact piece 36. A coil spring 37 is under compression between the arm 35 and the extension 25 heretofore described. A lug 38 seated in the arm 35 is adapted to successfully engage in notches 39 in a ring 40 that is held by means of screws 41 in the base of the casing, a notch being provided for each of the terminals 42 of the switch. A terminal 43 for current supply terminates in a contact ring 44 while a complementary ring 45 overlies the ring 44 and is mechanically connected to the driving sleeve 14 to be rotated thereby. A pair of flexible cables 46 are soldered to the ring 45 and conduct the current directly from the ring to the contact piece 36.

The operation of the mechanism thus far described is as follows:

With the parts in the position shown in the drawings, it will be seen that the switch arm 35 cannot be shifted until it is withdrawn perpendicularly from the contact faces, because of the interlocking of the lug 38 with one of the notches in the rim. This is brought about by reason of the fact that as the shaft is turned, the drive arm 18 through one of the shoulders 28-29 depresses one of the projections 30-31 of the bell-crank, thereby causing the switch arm to be moved away from contact engagement. The rotation of the drive arm 18 applies force to one of the spring ends 22-23 on the finger 24 that is fixed to the drive sleeve 26 and which sleeve carries the switch arm. Thus, when the switch arm has been swung backward sufficiently to disengage the lug 38 from its notch, the stored up force in the spring end will quickly snap the switch arm and its associated parts into the next position of the switch. The freedom of movement between the drive arm 18 and the switch arm that is permitted by the spring ends 22-23, permits the parts to resume their normal position immediately after the switch arm is released from the notch and thus it will snap into the next successive notch without the volition of the operator.

While in the construction shown I have shown the notch 39 as provided with straight sides, thus insuring an exact perpendicular movement of the switch arm in making and breaking contacts, yet I may prefer to somewhat incline the sides of the notches in order to secure a limited sliding movement of the contact pieces preliminary to breaking contact.

In the construction shown in Figs. 6 to 9, a similar result is secured by the use of quite different mechanism. In that construction the casing 47 has a cover 48 and a shaft 49 is mounted therein in the usual manner. Extending through the shaft 49 with capacity for limited freedom of movement is a pin 50 that serves to connect a sleeve 51. An oscillating switch arm 52 is pivoted to the sleeve 51 by means of a pin 53. A bracket 54 secured to the sleeve 51 serves as a support for a compression spring 55 that bears against the switch arm and tends to force it into contact engagement. A roller 56 carried by the outer end of the switch arm successively engages recesses 57 between projection 58 formed on the cover 48. One recess being provided for each contact to be made.

At its outer end the contact arm carries two contacts 59-60 the latter being connected through a leaf spring 61 to the arm. The set of the spring will be such that the contact 60 will first make engagement with the terminal piece 62. Thereafter the contact 59 will engage with the terminal piece 63 and conversely, in breaking the contact the pieces 60-62 will be last to break and will be subject to whatever arcing takes place.

Current is supplied through the terminal 64 to a ring 65. A rotating ring 66 driven by the shaft and insulated therefrom is connected by a flexible cable 67 to the contact piece 59-60.

It will be noted that the projections 58 have inclined sides. This with the lost motion provided between the shaft 49 and the sweep arm by the pin 50, insures that the break will be somewhat gradual relative to the lateral or angular motion. In other words, there will be a limited sliding motion but the contacts will be separated without sliding off the edge of the contact pieces. This insures also that the contact will be made with a snap action regardless of the volition of the operator.

In the construction of Figs. 10 to 14, the base or housing 68 remains the same, the housing having a cover 69. A plurality of switch points are provided, three, only, being shown in this instance. The arrangement of the switch points is novel in that a groove 70 is provided in the base, which is preferably constructed of a dielectric material, such as porcelain, the groove providing an inclined shoulder adapted to receive one switch point 71 of a pair, the other point 72 being arranged in the plane of the base. These points are mounted on a common terminal piece 73. The purpose for the angular arrangement of the respective points will be explained hereafter.

A shaft 74 is mounted in the casing, the lower end being received within an insulating sleeve 75, a transverse pin 76 in the shaft engaging with a slot in the sleeve to effect rotation in unison. The sleeve is provided with ears 77, engaged by lugs 78 formed on a disc 79 that constitutes a sliding contact with a terminal disc 80 connected to a terminal 81. A flexible cable 82 is soldered to the disc 79 at one end and at the other end to a twin piece 83. This contact piece carries contacts 84, 85 arranged at an angle corresponding to that of the points 71, 72.

The contact piece 83 is fixed on a dielectric block 86 that is pivoted at 87 to a sweep arm 88. A flat spring 89 connected to the arm bears at its outer end against the end of the block 86 and tends to swing the same as permitted by an arcuate slot 90 in the outer end of the block, the slot engaging a pin 91 carried by the arm. Thus as the contacts move toward a position to close the circuit, the contact 84 will, due to the action of the spring 89, first make engagement with the outer switch point 72. Continued travel of the sweep arm will serve to rock the block 86 on the pin 87 and as the contact 85 engages the point 71 a toggle action is secured. This is illustrated in Figs. 10 and 11 by the dotted line 87^x which extends from the pivot point 94 through the pivot point 87 to the center of the contact 85. In Fig. 11 it will be noted that the angle of the line is considerably greater than in Fig. 10, the line being nearly straight in the latter figure, showing a relatively great pressure is being exerted by the toggle action.

In this construction, the same as in the heretofore described, the sweep arm is caused to rock and to lift the contact from engagement with a

switch point as a preliminary to angular movement of the arm. This is brought about by the following construction.

5 A sleeve 92 is connected to the shaft 14 by means of a pin 93, the opening through the shaft being slotted as shown in Fig. 14 whereby to provide for a substantial loss of motion. The sweep arm is formed as a lever of the first order, being pivoted at 94 to the sleeve 92. A bracket 95 fixed 10 to the sleeve carries a loop spring 96 that bears against the outer end of the sweep arm and tends to force the contacts into circuit-closing position. The outer end of the sweep arm carries a roller 97 that engages with the teeth 98 of a circular 15 rack, a number of teeth being provided to correspond to the number of switch points. It will be noted that the sides of the teeth 98 are substantially straight and in order to effect an easy disengagement of the roller therefrom, I provide 20 a rotary cam piece 99 having less abrupt cams 100 than are provided on the teeth 98. The cam piece 99 is rigidly pinned at 101 to the shaft 14 without lost motion. Thus on the first turning movement of the shaft, the gradual cams 100 will 25 act on the roller 97 to force the roller out of the notch and to lift the contacts perpendicularly out of engagement with the switch point. When the roller has been lifted to a point near the upper 30 ends of the teeth 98, the pin 93 will then take effect to begin a turning movement of the sweep arm and the roller will ride over a tooth 98 and, on approaching the next succeeding notch, will immediately snap into the notch without the volition of the operator; this is due to the lost 35 motion between the shaft and the arm support sleeve.

40 A description of operation of the respective structures has been provided in connection with a description of the structure thereof. It may be said, however, that in each structure the sweep arm is designed to be lifted perpendicularly from circuit-making contact with only a very slight drag between the contacts. This arrangement has been found to be advantageous for various 45 reasons.

The term "point" or "switch point" as used in the claims is intended to comprehend a fixed contact of indefinite area; the term is used to distinguish, merely in terminology, from the contacts 50 carried by a switch arm.

It should also be understood that wherever in the claims I have described the sweep arm as pivoted or connected to the operating shaft I comprehend any construction in which an insulating sleeve is interposed between the arm and shaft, as well as a construction in which shaft insulation is not necessary and in which the arm is directly rather than indirectly connected to the shaft.

60 Obviously other modifications may be made than those shown and I do not wish to be limited, except as indicated in the appended claims.

1. In combination, a base having a series of switch points, a cover, a shaft axially arranged 65 relative to the points, a sweep arm in the form of a lever of the first order pivoted to said shaft for oscillation thereon and rotation thereby, said arm carrying a contact, a bracket projecting from and rotatable with said shaft, a spring acting 70 between said bracket and the end of the arm

opposite to the contact, and a series of cams carried by the cover acting on said arm, causing the same to oscillate as a preliminary to movement of the arm away from a switch point.

2. In a switch, the combination of a base having switch points, a cover, a shaft axially arranged relative to the points, a sweep arm rotatable by the shaft and pivoted thereto with capacity for oscillation, means providing for substantial lost motion in the connection that provides for rotation of the arm by the shaft, means carried by the cover providing a series of notches corresponding in number to the switch points, said notches coacting with the arm to raise the arm out of contact prior to movement of the arm from the plane of a switch point, the said lost motion permitting said arm to engage the next succeeding notch in advance of completion of rotation of the shaft.

3. In combination, a base having a series of switch points, a shaft axially arranged relative to the points, a sweep arm in the form of a lever of the first order pivoted to said shaft for oscillation and rotation thereby, said arm carrying a contact, a bracket projecting from and rotatable with said shaft, a spring acting between said bracket and the end of the arm opposite to the contact, and a series of cams acting on said arm causing the same to rock as a preliminary to movement of the arm away from a switch point.

4. In a switch, the combination of a base having switch points, a shaft axially arranged relative to the points, a sweep arm rotatable by the shaft and pivoted thereto with capacity for oscillation, means providing for substantial lost motion in the connection that provides for rotation of the arm by the shaft, means providing a series of notches corresponding in number to the switch points said notches coacting with the arm to raise the arm out of contact prior to movement of the arm from the plane of a switch point, the said lost motion permitting said arm to engage the next succeeding notch in advance of completion of rotation of the shaft.

5. In combination, a base having points, a shaft centrally arranged relative to said points, a sleeve surrounding the shaft and connected thereto with capacity for substantial lost motion, a sweep arm mounted to rock on said sleeve, said arm having a contact, means remote from the points for causing the arm to rock, and to raise the arm from the points, said lost motion and said arm-raising means acting to permit the arm to drop and engage a point in advance of rotation of the shaft.

6. In combination, a base having points, a shaft centrally arranged relative to said points, a sleeve surrounding the shaft and connected thereto with capacity for substantial lost motion, a sweep arm mounted to rock on said sleeve, said arm having a contact, means remote from the points for causing the arm to rock, and to raise the arm from the points, said lost motion and said arm-raising means acting to permit the arm to drop and engage a point in advance of rotation of the shaft, a terminal rotatable with the shaft and insulated therefrom, and a flexible cable connecting the terminal to the contact.

DAVID T. SIEGEL. 70
